CHAIR AND FRICTION HINGE THEREFOR

Filed March 11, 1929

UNITED STATES PATENT OFFICE

ARTHUR C. BROWN, OF WAKEFIELD, MASSACHUSETTS, ASSIGNOR TO HEYWOOD-WAKEFIELD COMPANY, OF BOSTON, MASSACHUSETTS, A CORPORATION OF MASSACHUSETTS

CHAIR AND FRICTION HINGE THEREFOR

Application filed March 11, 1929. Serial No. 345,992.

This invention relates to friction hinge devices and while not limited thereto has been more particularly developed to meet the requirements of folding chairs whereby the 5 hinged parts may be retained without the use of the other means in any relative position to which they may be adjusted. As applied to the mounting of the seats of chairs, this prevents the seats from dropping open as 10 soon as folding pressure is removed when they have been partly folded, this serving to prevent the disturbing and often startling noise which results from such dropping.

For a more complete understanding of this 15 invention, reference may be had to the accompanying drawing in which

Figure 1 is a side elevation of a chair showing the device in dotted lines.

Figure 2 is a section to a much larger scale 20 on line 2—2 of Figure 1.

Figure 3 is a section on line 3—3 of Figure 2.

Figures 4 and 5 are perspectives of the friction elements of the device.

25 Referring to this drawing, at 1 is indicated a chair side frame member to which the seat 2 is pivoted as at 3. At 4 is shown a combined leg and stop having its forward upper end 5 positioned to receive and support the seat 30 2 forwardly of the pivot 3 to define the open position of the seat. This member 4 is shown as pivoted at 6 to the frame member 1, thus permitting this member 4 to be folded when the seat 2 is turned up so as to lie closely adjacent to the frame member 1. At 7 is shown the usual brace extending from side to side of the chair at the back between the members 4. The hinge device at 3 forms more particularly the subject matter of the present invention.

40 As shown it comprises a pivot member 10 having a reduced diameter portion 11 at its outer end, a portion 12 of somewhat larger diameter inwardly of the portion 11 and defining therewith an annular shoulder 13 and 45 an inner end portion 14 of still larger diameter defining with the portion 12 an annular shoulder 15. The portion 14 is intended to be seated in a suitable socket 16 in the side frame member 1, the shoulder 15 being substantially flush with the inner face of the member 1.

At 20 is shown a wear plate apertured to engage over the portion 12 of the pivot member and resting against the inner face of the member 1 and against the shoulder 15 and held against rotation relatively to the member 1. This wear plate as shown is substantially circular in outline with a central perforation and with an extension 21 having riveted thereto or spun therein a pin 25 adapted to be seated in a socket 26 also in the frame member 1. This pin 25 engaging in the socket 26 holds the plate 20 against rotation relative to the frame member 1. Carried on the portion 11 beyond the wear plate and against the shoulder 13 is a friction plate 30 which is dished, its concave side facing the wear plate 20 so that its outer edges contact therewith under pressure. As shown the friction plate 30 is held against rotation relative to the pivot member 10, the portion 11 having a flat face 27 and the plate 30 having a correspondingly shaped central aperture 28. At 31 is shown a member carried on the portion 11 and having an extension 32 which may be fixed as by means of the screws 33 to the lower face of the seat 2. The outer end of the pivot member 10 is shown as riveted over the member 31 as at 35, this riveting serving to bind the member 31 against rotation relative to the pivot 10 and against the friction plate 30 so that all may rotate as a unit relative to the wear plate 20 and forcing the friction plate 30 into the desired frictional engagement with the wear plate. This riveting over, of course, is done prior to the attachment of the seat 2 thereto and in the course of manufacture of the hinge device. The friction element 30 is thus held to rotate with the element 31 and has sufficient frictional engagement with the wear plate 20 so that the seat 2 will be retained in any angular position in which it may be placed. It is thus prevented from falling by its weight onto the end portion 5 of the member 4 when it has been partly turned up so that it is impossible for the chair seat to drop open with its resulting disturbing noise.

Having thus described an embodiment of this invention, it should be evident to those skilled in the art that various changes and

modifications may be made therein without departing from its spirit or scope as defined by the appended claims.

I claim:

- 5 1. A device of the class described comprising a pivot having a reduced diameter portion and a pair of portions of larger cross section and forming a pair of spaced shoulders at one end of said reduced diameter portion, a wear 10 plate apertured to receive the smaller of said larger diameter portions and engaging against one of said shoulders, a dished friction plate on said reduced diameter portion, said plate having its concave side positioned against said wear plate and being rotatable relative thereto, and a member carried by said reduced diameter portion beyond said friction plate, said reduced diameter portion being headed over said member to press said member against said friction plate and said friction plate against said wear plate, said wear plate and member being adapted for attachment to members to be pivotally connected by said device.
- 15 2. In combination, a pair of members, a pivot element carried by one of said members, a flat wear plate outwardly of which said pivot element projects, means for holding said plate against rotation relative to said one member, a dished friction plate carried by said element and rotatable with its peripheral margin in frictional engagement with said wear plate, and means for fixing said friction plate against rotation relative to the 20 other of said members.
- 25 3. In combination, a rotatable pivot element having a circumferential shoulder, an apertured wear plate having said pivot extending through its aperture, said plate resting against said shoulder, a pin projecting from the face of said wear plate adjacent to said shoulder, a friction plate having a portion frictionally engaging the face of said wear plate remote from said shoulder and rotatable with said element, and a member to 30 be rotated secured to said element and pressing said friction plate against said wear plate.

In testimony whereof I have affixed my signature.

ARTHUR C. BROWN.
